(57) **CLAIM**

The ornamental design for a product package for absorbent articles, as shown and described.

DESCRIPTION

The file of this patent contains at least one drawing executed in color. Copies of this patent with color drawings will be provided by the Office upon request and payment of the necessary fee.

FIG. 1 is a perspective view of a first embodiment showing a top, right side and front view of a product package for absorbent articles;

FIG. 2 is a top view of the embodiment of the package shown in FIG. 1;

FIG. 3 is a front view of the embodiment of the package shown in FIG. 1;

FIG. 4 is a bottom view of the embodiment of the package shown in FIG. 1;

FIG. 5 is a back view of the embodiment of the package shown in FIG. 1;

FIG. 6 is a left side view of the embodiment of the package shown in FIG. 1; and

FIG. 7 is a right side view of the embodiment of the package shown in FIG. 1.

FIG. 8 is a perspective view of a second embodiment showing a top, right side, and front view of a product package for absorbent articles;

FIG. 9 is a top view of the embodiment of the package shown in FIG. 8;

FIG. 10 is a front view of the embodiment of the package shown in FIG. 8;

FIG. 11 is a bottom view of the embodiment of the package shown in FIG. 8;

FIG. 12 is a back view of the embodiment of the package shown in FIG. 8;

FIG. 13 is a left side view of the embodiment of the package shown in FIG. 8; and

FIG. 14 is a right side view of the embodiment of the package shown in FIG. 8.

FIG. 15 is a perspective view of a third embodiment showing a top, right side, and front view of a product package for absorbent articles;

FIG. 16 is a top view of the embodiment of the package shown in FIG. 15;

FIG. 17 is a front view of the embodiment of the package shown in FIG. 15;

(Continued)

FIG. 18 is a bottom view of the embodiment of the package shown in FIG. 15;
 FIG. 19 is a back view of the embodiment of the package shown in FIG. 15;
 FIG. 20 is a left side view of the embodiment of the package shown in FIG. 15; and
 FIG. 21 is a right side view of the embodiment of the package shown in FIG. 15.
 FIG. 22 is a perspective view of a fourth embodiment showing a top, right side, and front view of a product package for absorbent articles;
 FIG. 23 is a top view of the embodiment of the package shown in FIG. 22;
 FIG. 24 is a front view of the embodiment of the package shown in FIG. 22;
 FIG. 25 is a bottom view of the embodiment of the package shown in FIG. 22;
 FIG. 26 is a back view of the embodiment of the package shown in FIG. 22;
 FIG. 27 is a left side view of the embodiment of the package shown in FIG. 22; and,
 FIG. 28 is a right side view of the embodiment of the package shown in FIG. 22.
 Broken lines are included for the purpose of illustrating environment and form no part of the claimed design.
